CLOSURE AND REINFORCER FOR CIGARETTE AND LIKE PACKAGES

Elsie Fayer and Max Gonick, New York, N. Y.

Application November 4, 1938, Serial No. 238,714

6 Claims. (Cl. 206—41.2)

This invention relates to new and useful improvements in a closure and reinforcer for cigarettes and the like packages.

More specifically, the invention proposes the construction of a closure and reinforcement for cigarette and the like packages characterized by the provision of a sheet material body having vertical sides and end walls for encasing the ends of the cigarettes and being disposed between the cigarettes and the inner walls of the package.

Still further the invention proposes the provision of a top wall connecting the central portions of the side walls of the body in a particular manner to form openings at the ends of said body through which cigarettes may be ejected when one corner of the package is torn open.

Still further the invention proposes the provision of a slide mounted intimately below the top wall of said body and slidably mounted on the side walls in a manner to be extended across either of the end openings in said body to close the said openings regardless of which corner of the package is torn open.

Another object of this invention is the provision of a pair of slides mounted below said top wall and each being independently extendable across one of the end openings in said body for closing the same.

Another object of this invention is the provision of a means for mounting the slide or slides upon the side walls of said body in a particular manner to be extendable across said openings.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:

Fig. 1 is a perspective view of a cigarette package having a closure and reinforcer constructed according to this invention.

Fig. 2 is a sectional view of Fig. 1.

Fig. 3 is a perspective view of the closure and reinforcer per se.

Fig. 4 is a sectional view on the line 4—4 of Fig. 3.

Fig. 5 is a sectional view on the line 5—5 of Fig. 3.

Fig. 6 is a sectional view of a closure and reinforcer constructed according to a modification of the invention.

Fig. 7 is a sectional view on the line 7—7 of Fig. 6.

Fig. 8 is a side elevational view of a closure and reinforcer constructed according to another embodiment of this invention.

Fig. 9 is a sectional view on the line 9—9 of Fig. 8.

Fig. 10 is a fragmentary perspective view, similar to Fig. 3 but illustrating another form of the invention.

Fig. 11 is a vertical sectional view on the line 11—11 of Fig. 10.

Fig. 12 is another perspective view similar to Fig. 3, but illustrating a still further modified form of the invention.

Fig. 13 is a perspective view of a modified slide leaf.

Fig. 14 is a similar view to Fig. 6 but illustrating the arrangement shown in Figs. 12 and 13.

The closure and reinforcer for cigarette and the like packages, according to this invention, includes a sheet material body 10 having vertical side walls 10^a and end walls 10^b for engaging within the top portion of a cigarette package 11 immediately adjacent the cigarettes 12 contained therein. The sheet material body 10 is constructed of sheet metal or other material and is integrally formed with a top wall 10^c which connects the central portions of the top edges of the side walls 10^a. In forming the sheet material body the ends of the side walls 10^a are bent inwards and secured together in face contact as shown in Fig. 3 for forming the end walls 10^b. The ends of the cigarettes 12 are adapted to be inserted into the sheet material body 10 before the package 11 is engaged therearound.

The package 11 consists of an inner wrapper 11^a of paper or other material upon which a wrapper 11^b of a metallic foil is mounted. A second paper wrapper 11^c is superimposed upon the metallic foil wrapper 11^b and extends only to the top of the package 11 and is imprinted on its outer face with a suitable design and the name of the cigarette. A Cellophane wrapper 11^d is positioned upon the paper wrapper 11^a and the upper ends of the paper wrapper 11^a, the metallic foil wrapper 11^b, and the Cellophane wrapper 11^d are folded over the top end of the cigarettes 12 as shown in Fig. 2. The top wall 10^c of the sheet material body 10 lies immediately adjacent the paper wrapper 11^a where it is folded over the top of the cigarettes 12.

A slide 13 is slidably mounted intimately beneath the top wall 10^c of the sheet material body 10 and upon the side walls 10^a and is adapted

to be extended in one direction or the other to close the top openings of said body to either side of the top wall 10^c.

The side walls 10^a adjacent the top edges thereof are formed with inwardly extending grooves 10^{aa}, while the top edges of the side walls 10^a are bent inwards forming tracks 14 into which the edges of the slide 13 are extended for slidably supporting the same to permit the slide to be extended in either direction with relation to the top wall 10^c.

The ends of the slide 13 are formed with outwardly extending lugs 15 stamped from the material of the slide and bent upwards to form abutments behind which one's finger nail may be engaged for moving the slide in either direction. The upwardly extending lugs 15 are resilient in construction and when engaged beneath the top wall 10^c they act to hold the slide 13 in a closed position to prevent it from accidentally moving to an open position.

The operation of this device is as follows:

The closure and reinforcement is mounted within the cigarette package at the time when the cigarettes are packed. When purchased the customer opens one corner of the package in the conventional manner for exposing the upper ends of a cigarette 12 to permit its removal through the end openings formed in the sheet material body 10. After the removal of the desired cigarette, and regardless of which corner of the package is opened, the slide 13 may be extended across the open end opening of the sheet material body for closing the package to prevent the cigarettes from drying out.

In extending the slide 13 across the open end of the sheet material body 10 one's finger nail is engaged behind the proper lug 15 and the slide manually pushed in the desired direction for closing the said opening.

According to the embodiment of the invention shown in Figs. 6 and 7 the slide 13 is constructed of separate slide members 13^a which are mounted in superimposed positions below the top wall 10^c of the sheet material body 10. Each of the slides 13^a is slidably supported in one pair of superimposed tracks 14' formed in the side walls 10^a adjacent the top edges thereof. Opposite ends of the slide members 13^a are formed with upwardly extending lugs 15 forming abutments for one's finger nail to permit the slide to be engaged across the open ends of the sheet material body. The side walls 10^a may be glued or cemented as at 10^d either at one or both sides 55 to the inner wall of the inner wrapper 11^a of the package. In other respects this form of the invention is similar to the previous form.

According to the modification shown in Figs. 8 and 9 the construction of the closure and reinforcement is similar to that disclosed in Figs. 1 to 5 and differs therefrom in the means for slidably supporting the slide 13'. In this form of the invention the slide 13' is slidably supported by means of headed studs 16 which are mounted upon the sides of the slides 13'. The shank portions 16^a of the headed studs 16 pass through elongated slots 17 formed in the side walls 10^a adjacent the top edges thereof in a manner to permit the slide to be immediately adjacent the bottom face of the top wall 10^c. In other respects this form of the invention is similar to the previous form.

In Figs. 10 and 11 the end wall 10^b is shown with a downward projection 10^{bb} to reinforce the vertical end wall of the package. The side walls

10^a of the reinforcing device are formed with cut-out portions 20 which permits ready gripping of the cigarettes within the package. The slide 13'' is provided with complementary tab portions 21 which project downwardly in alignment with the cutout portion 20, when the slide 13'' is pulled into closing position. The tabs 21 may be folded upwardly to permit ready sliding of member 13'' and may also be used as a handle for pulling the slide. In other respects this form of the invention is similar to the previous form.

In Figs. 12, 13 and 14 the top wall 10^{cc} is provided with 2 slots 22, to form a center portion 23 of the top wall 10^{cc} which is depressed so as to permit the slide 13'' to be supported above the center portion 23 and below the outer portions 24 of the top wall 10^{cc}. In this form of the invention 2 slide members 13'' may be used which are similar to the prior forms.

It is to be understood that this reinforcer 20 may be of any suitable size and material and may be used either at one or both ends of cigarette or like packages.

While we have illustrated and described the preferred embodiments of our invention, it is to be understood that we do not limit ourselves to the precise construction herein disclosed and the right is reserved to all changes and modifications coming within the scope of the invention as defined in the appended claims.

Having thus described our invention, what we claim as new, and desire to secure by United States Letters Patent is:

1. A closure and reinforcement for cigarette and the like packages, comprising a sheet material body having vertical side and end walls for engaging within the top portion of a cigarette package immediately adjacent the wrapping thereof and a top wall connecting the central portions of the top edges of the side walls, a slide intimately beneath said top wall and slidably mounted on said side walls and adapted to be extended in one direction or the other to close the top openings of said body to either side of said top wall, said slide at its ends being formed with upwardly extending lugs forming abutments for one's finger nail to permit said slide to be moved in the proper direction for closing the open end of said body.

2. A closure and reinforcement for cigarette 50 and the like packages, comprising a sheet material body having vertical side and end walls for engaging within the top portion of a cigarette package immediately adjacent the wrapping thereof and a top wall connecting the central portions of the top edges of the side walls, a slide intimately beneath said top wall and slidably mounted on said side walls and adapted to be extended in one direction or the other to close the top openings of said body to either side 60 of said top wall, said slide at its ends being formed with upwardly extending lugs forming abutment for one's finger nail to permit said slide to be moved in the proper direction for closing the open end of said body, said lugs being resilient in construction and engageable against the bottom face of said top wall for holding said slide in its closed position.

3. A closure and reinforcement for cigarette 70 and the like packages, comprising a sheet material body having vertical side and end walls for engaging within the top portion of a cigarette package immediately adjacent the wrapping thereof and a top wall connecting the central portions of the top edges of the side walls,

- a slide intimately beneath said top wall and slidably mounted on said side walls and adapted to be extended in one direction or the other to close the top openings of said body to either 5 side of said top wall, said side walls having their ends turned inwards and securely attached together in face contact for holding said end walls, said slideably mounting of said slide comprising grooves formed in said side walls forming tracks 10 in which the sides of said slide are slidably engaged, cutout portion in the upper edges of the said side wall, near their turned in portions, to facilitate the removal of the cigarettes from the package, complementary downwardly projecting tabs on said slide adapted to close the said 15 cutout portion when the slide is in closing position.
4. A closure and reinforcement for cigarette and the like packages, comprising a sheet of material adapted to be extended across the top of a cigarette or the like package intermediate of its ends forming a partial top wall leaving the 20 ends of the top exposed, side portions continuing from the sides of said sheet of material and bent at right angles to said sheet of material to extend along the sides of said package, a slide 25 intimately beneath said partial top wall and slidably supported on said side portions and adapted to be extended to either side of said partial top wall to close the top of said package to either 30 side of said top wall, said side portions having their ends directed towards each other and overlapped and securely attached together to prevent 35 said side portions from spreading and releasing said slide.
5. A closure and reinforcement for cigarette and the like packages, comprising a sheet of material adapted to be extended across the top of a cigarette or the like package intermediate of its ends forming a partial top wall leaving the 40 ends of the top exposed, side portions continuing from the sides of said sheet of material and bent at right angles to said sheet of material to extend along the sides of said package, a slide 45 intimately beneath said partial top wall and slidably supported on said side portions and adapted to be extended to either side of said partial top wall to close the top of said package to either 50 side of said top wall, said side portions having their ends directed towards each other and overlapped and securely attached together to prevent 55 said side portions from spreading and releasing said slide, said side portions being formed with inwardly extending cutouts for facilitating the removal of the cigarettes from said package, and means on said slide for closing said cutouts when said slide is in its closed position.
6. A closure and reinforcement for cigarette and the like packages, comprising a sheet of material adapted to be extended across the top of a cigarette or the like package intermediate of its ends forming a partial top wall leaving the 60 ends of the top exposed, side portions continuing from the sides of said sheet of material and bent at right angles to said sheet of material to extend along the sides of said package, a slide 65 intimately beneath said partial top wall and slidably supported on said side portions and adapted to be extended to either side of said partial top wall to close the top of said package to either 70 side of said top wall, said side portions having their ends directed towards each other and overlapped and securely attached together to prevent 75 said side portions from spreading and releasing said slide, said side portions being formed with inwardly extending cutouts for facilitating the removal of the cigarettes from said package, and means on said slide for closing said cutouts when said slide is in its closed position, comprising 80 downwardly extending projections formed on said slide and alignable with said cutouts.
